Patented Oct. 14, 1975

237,156

BICYCLE REFLECTOR

Bennie L. McEwin, 352 E. Papago Drive,
Tempe, Ariz. 85281

Filed Dec. 10, 1973, Ser. No. 423,523

Term of patent 14 years

Int. Cl. D10—06

U.S. Cl. D10—111

FIG. 1

FIG. 2

FIG. 3

FIG. 4

FIG. 1 is a front perspective view of a bicycle reflector showing my design;

FIG. 2 is a rear perspective view thereof;

FIG. 3 is a front elevational view thereof;

FIG. 4 is a top plan view thereof on an enlarged scale.

I claim:

The ornamental design for a bicycle reflector, as shown and described.
